US00D734895S

(12) **United States Design Patent**
Liu(10) **Patent No.:** **US D734,895 S**
(45) **Date of Patent:** **** Jul. 21, 2015**(54) **COSMETICS CONTAINER**(71) Applicant: **International Cosmetic Suppliers Ltd.,**
Taipei (TW)(72) Inventor: **Jeffrey Liu, Taipei (TW)**(73) Assignee: **INTERNATIONAL COSMETIC**
SUPPLIERS LTD., Taipei (TW)(***) Term: **14 Years**(21) Appl. No.: **29/475,725**(22) Filed: **Dec. 5, 2013**(51) LOC (10) Cl. **28-03**

(52) U.S. Cl.
